UNITED STATES PATENT OFFICE

GEORGE THOMAS BRADO, OF RENO, NEVADA

BURNER

Application filed January 28, 1929. Serial No. 335,612.

My invention relates to improvements in burners, and it consists in the combinations, constructions and arrangements hereinafter described and claimed.

5 An object of my invention is to provide a novel type of device for changing liquid fuel into a vapor prior to the burning of the fuel. The device is designed to cause the liquid fuel to flow over a series of heated plates and 10 to drop from one plate to another until all of the fuel is vaporized. The device directs the vapor toward one end where it is burned.

A further object of my invention is to provide a device of the type described which may 15 be quickly assembled and placed in a burner without the necessity of fastening the device in place.

Other objects and advantages will appear as the specification proceeds, and the 20 novel features will be particularly pointed out in the appended claims.

My invention is illustrated in the accompanying drawing forming a part of this application, in which

25 Figure 1 is a longitudinal section through the device;

Figures 2 and 3 are sections along the lines 2—2 and 3—3 of Figure 1; and

Figure 4 is a perspective view of the vapor- 30 izing device.

In carrying out my invention, I make use of a furnace 1 or other type of heater, and I dispose a burner indicated generally at 2 partly within the furnace. The furnace has an 35 opening 3 for receiving the burner.

It should be noted that the burner is divided into two compartments A and B, and that these are partially separated from each other by an upwardly-extending rib 4. A curved 40 tongue 5 extends downwardly into the compartment B from the top of the burner. An air pipe 6 leads into the compartment B, and the compartment A is provided with a large opening 7 through which the burning vapor 45 passes.

Within the compartments A and B, I dispose a vaporizing device indicated generally at 8. Figures 3 and 4 show this device as being composed of three plates 9, 10 and 11. I 50 preferably make each of these plates out of

a composition consisting of one part zinc, two and one-half parts copper, and one and one-half parts block tin.

The plate 11 is supported by legs 12 and rests upon the bottom of the burner 2. The plate has a hollowed-out recess 13 that is somewhat trough-shaped, having upwardly-extending sides 14 and an upwardly-extending end 15 (see Figure 1). The opposite end is not provided with a fuel-retaining flange or side.

55 The sides 14 have grooves 16 for receiving the flanges 17 of the top plate 9 (see Figure 3). The center plate 10 is carried by the inclined inner surfaces of the sides 14 and is spaced a slight distance away from the upturned end wall 15. It is also to be noted from Figure 1 that the center plate 10 terminates short of the open end of the plate 11.

60 The plates 9 and 10 are perforated, and the perforations of one plate are staggered with respect to those of the other in order to prevent the dropping of the oil directly from the top plate to the bottom plate. The top plate 9 has side walls 18 and an end wall 19. This plate is further provided with a cavity 20 on its under surface. Figure 1 shows that the plate 9 terminates short of the plate 10 at the left-hand side of the device, but that the plate 9 has an end wall 75 21 that corresponds with the end wall 15. These two end walls abut one another and have aligned recesses for forming an opening 22 through which air passes.

65 A gravity fuel pipe 23 leads into the burner and has its end turned so as to overlie the rear of the top plate 9. Fuel flowing to this burner will come directly into contact with the incoming air flowing through the pipe 6 before striking the plate 9. The fuel will 70 then strike upon and will flow over the top of the plate 9 and will be partially vaporized due to the heated plate. The unvaporized fuel will trickle through the openings 24 in the plate 9 and will drop upon the heated 75 plate 10 where a further vaporization of the fuel will take place. Any fuel not vaporized at this point will pass on down through the openings 25 in the plate 10 and will be vaporized in the bottom plate 11.

During all this vaporization, air is being intimately mixed with the vapors. The vapor rising from the plate 9 will be mixed with air flowing directly from the pipe 6. A part of the air flowing from the pipe 6 will pass through the opening 22 and there will be divided, a portion passing above the plate 10 and another passing beneath the plate 10. This air will be mixed with the vapor rising from the plates 10 and 11.

The stepped arrangement of the plates 9, 10 and 11 provide openings at the left-hand side of the vaporizing device through which the vapor passes. This vapor is instantly ignited by the flame, and this flame passes through the opening 7 and on into the furnace 1. This flame keeps the plates hot, and thus provides a simple automatic means for forming additional vapor so long as the device functions.

In Figure 3, I show a fuel pipe 26 controlled by a valve 27. The pipe 26 communicates with the pipe 23. The pipe 26 is supported by a stub pipe 28 that is carried by the burner 2. The pipe 28 is not designed to carry fuel, but is merely a support.

Although I have shown and described one embodiment of my invention, it is to be understood that the same is susceptible of various changes, and I reserve the right to employ such changes as may come within the scope of the invention as claimed.

I claim:

1. A vaporizer comprising a bottom plate having a shallow trough, an intermediate plate supported by the side walls of the trough and terminating short of one end of the trough, and a top plate having a recess in each of its top and bottom surfaces and terminating short of the intermediate plate on the end nearest the foregoing end of the trough, the opposite end of the top plate and the adjacent end of the bottom plate abutting each other and having recesses which coact to provide an opening for the passage of air above and below the intermediate plate, said top and intermediate plates having openings staggered with respect to each other.

2. A vaporizer comprising a bottom plate having a shallow trough, an intermediate plate supported by the side walls of the trough and terminating short of one end of the trough, and a top plate having a recess in each of its top and bottom surfaces and terminating short of the intermediate plate on the end nearest the foregoing end of the trough, the opposite end of the top plate and the adjacent end of the bottom plate abutting each other and having recesses which coact to provide an opening for the passage of air above and below the intermediate plate, said top and intermediate plates having openings staggered with respect to each other, the composition of each plate consisting of one part zinc, two and one-half parts

copper, and one and one-half parts block tin. 3. A vaporizer comprising a top, a middle and a bottom member superimposed one above the other and forming two passageways, said top and bottom members having abutting ends and provided with recesses which coact to form an air receiving opening.

GEORGE THOMAS BRADO.
